CLAIM

The ornamental design for an athletic shoe cleat cleaner, as shown and described.

DESCRIPTION

FIG. 1 is a perspective view of an athletic shoe cleat cleaner showing my new design;

FIG. 2 is a top plan view thereof;

FIG. 3 is a bottom plan view thereof;

FIG. 4 is a front elevational view thereof;

FIG. 5 is a rear plan view thereof;

FIG. 6 is a left side elevation view thereof; and,

FIG. 7 is a right side elevation view thereof.

The athletic shoe used with the invention is shown in broken lines for illustrative purposes only and forms no part of the claimed design.
